TURNTABLE SPEED GOVERNOR

Colin B. Dale, Oak Park, Ill., assignor to Philco Radio and Television Corporation, Philadelphia, Pa., a corporation of Delaware

Application October 24, 1941, Serial No. 416,418

11 Claims. (Cl. 74—206)

This invention relates to self-governing drive means for turntables. More particularly, the invention has reference to such drives useful in combination recording and reproducing phonographs, which drives in addition utilize a small wheel engaging the inner edge of a depending turntable flange.

In recent years there has been a growing demand for home phonographs capable of recording records as well as reproducing the same, and this has led to certain problems in connection with the phonograph drive means. It is desirable to keep such instruments relatively inexpensive in price, and for this reason they are often supplied with an induction motor, as such motors are comparatively economical to construct.

However, experience has shown that inexpensive turntable drives, especially when powered by the above type of motor, may not be entirely satisfactory as the motor is incapable of driving the turntable at an unvarying speed from start to finish of a record, particularly during the recording operation. During recording, there is a wide variation in the number of inch-ounces of resistive effort exerted by the cutting stylus between its positions at the beginning and at the end of the record. Similarly, the load applied to the turntable may vary considerably during the playing or recording of loud and soft passages.

As is well known, the above-mentioned load variations will often cause variations of the turntable speed, and thereby result in objectionable variations in the tempo and pitch of recordings made upon such machines.

It is, therefore, the primary object of the present invention to overcome the aforesaid difficulties by the provision of a self-compensating turntable drive which ensures a uniform rotational speed, regardless of variations in the force applied to the turntable, or the lever arm through which this force is acting.

It is a more particular object of this invention to provide, in a phonograph drive mechanism of the type utilizing a wheel driven from the face of a disc, a movably mounted shaft arranged to move said wheel to a disc area of higher surface speed, in response to an increase in the load upon the turntable.

A further object of the present invention resides in the provision of a governor mechanism of the above type which is simple to construct and positive in its action, being responsive to very minute fluctuations in turntable speed.

The manner in which the above and other ob-

jects and advantages are realized will be best understood by considering the following description taken with the accompanying drawings, in which:

5 Fig. 1 is a side elevational view of a phonograph drive mechanism incorporating the present invention;

10 Fig. 2 is a top plan view of the mechanism shown in Fig. 1, with the turntable and base-plate shown in dot-and-dash outline;

Fig. 3 is a sectional view taken along line 3—3 of Fig. 1;

15 Fig. 4 is a detail sectional view on a larger scale of a portion of the drive mechanism; and

Fig. 5 is a detail sectional view taken along line 5—5 of Fig. 4.

Referring more particularly to the drawings, Fig. 1 illustrates the essentials of one form of drive mechanism with which this invention is especially useful.

20 This mechanism comprises a main baseplate 1 having a central recessed portion 2 to accommodate the conventional turntable 3, which may be mounted for rotation about a central spindle 25 4 by means of a suitable bearing (not shown). The cooperating tone arm and amplifier may be any well known type, and hence need not be here illustrated or described.

Beneath the baseplate 1, a pair of depending 30 arms 5—5 are pivotally connected to a pair of apertured lugs 6—6, formed on a generally horizontal bracket 7. A constant speed electric motor 8 carrying a driving disc 9, is supported on bracket 7, as by semi-resilient mounting 35 blocks 10. A generally bell shaped wheel 11 is in driven engagement with the face of disc 9, and is attached to a short shaft 12 (see Fig. 4), which carries a small turntable driving wheel 13 at its upper end. This wheel is preferably made 40 of rubber, or some other suitable frictional material. The construction and mounting of members 11, 12 and 13 will be fully brought out hereinafter.

The arrangement of disc 9, wheel 11 and bracket 7 is such that the speed of rotation of the turntable 3 will be determined by the point of contact between the disc and its cooperating wheel, that is, the greater the driving radius of disc 9, the greater the turntable speed.

45 In the embodiment illustrated, the turntable speed is not only automatically regulated in a manner to be hereinafter described, but is manually adjustable, by raising or lowering the bracket 7. This adjustment is effected by rotating the control knob 14, which serves to oscillate

a bell crank 15 (see Fig. 3) connected to bracket 7 by means of a rod 16. This manual adjustment of the driving ratio, by raising and lowering the bracket 7, need not be described further, as it forms no part of the present invention, per se, and is fully described and claimed in the co-pending application of Elmer O. Thompson, Serial No. 412,654 filed September 27, 1941.

As is best shown in Figs. 2, 4 and 5, shaft 12, which carries wheels 11 and 13, is supported in a novel manner now to be described. Bracket 7 carries a small U-shaped member 11 which in turn carries a bearing block 18, pinned to bracket 17 by a pivot member 19. The lower end of shaft 12 is mounted for rotation in block 18 by means of a bearing insert 20. As will be apparent from the drawings, this assembly provides a main pivot point about which the longitudinal axis of shaft 12, and its associated wheels 11 and 13, may swing, thereby varying the effective driving radius of disc 9, as indicated in Fig. 1. Bracket 7 is apertured at 21 to accommodate the lower end of shaft 12. This is necessary when the bracket 7 is capable of manual adjustment, in accordance with said copending Thompson application.

Making particular reference to Figs. 2 and 4, it will be seen that the upper end of shaft 12 is supported by a lever 22, pinned to the baseplate as at 23, by means of an elongated aperture 24 formed in said lever. The lever is urged outwardly from pivot 23 by means of a spring 25 fixed to a lug on the baseplate, as at 26. At its free end, lever 22 has a cup-shaped depression 27 (Fig. 4) through which the shaft 12 passes. A bearing 28 is seated in the cup 27, and is prevented from rotating by means of a lug 29, which extends into a recess in bearing 28. Washers 30 and 31 serve to maintain the proper relationship of the above described bearing elements, mounting the shaft for rotation, while still permitting a slight rocking of shaft 12 as the lever 22 swings about its pivot 23. Wheel 13 and collar 32 (held by set screw 33) cooperate to maintain the above-described elements in assembled relation and to prevent longitudinal movement of shaft 12 relative to lever 22.

A second spring 34, is provided, and is adjustably fixed to the baseplate at 35. A pair of stop members 36 and 37 (the last named being provided with an eccentric pivot to provide adjustability thereof) limit the angular movement of lever 22 to a desired range, and as will be seen from Fig. 2, the two spring members move lever 22 in a direction to urge wheel 13 into firm contact with the inner edge of the depending turntable flange.

The operation of the device is as follows:

With the direction of turntable and driving wheel rotation as shown in Fig. 2, wheel 13 will tend to move around the edge of turntable 3 (in response to the resistance to rotation presented by the turntable and its cooperating stylus) in a direction to move lever 22 toward stop 37. The position of the parts shown in Fig. 2, with the lever closely adjacent stop 36, is the no-load condition. When the stylus is placed upon the record, wheel 13 will move somewhat, as above described, against the tension of spring 34 and assume a balanced position, between stops 36 and 37. The screw 38 provides ready adjustability of the tension of spring 34, and thereby ensures that lever 22 will find its proper balanced position. Upon a sudden variation in the resistive effort exerted by the stylus, turntable 3 will tend to slow down or increase its speed, as the

case may be, and wheel 13 will seek a new position. As best seen in Fig. 1, this movement of wheel 13 will cause shaft 12 to swing about its lower pivot 19, thereby changing the position of wheel 11 with relation to disc 9. The relation of the rotating parts, and the disposition of pivot 19, is such that movement of wheel 13 toward either of stops 36 and 37 will move wheel 11 in a direction to restore the proper speed of turntable 3. For example, increases in the resistive load presented by the turntable, will first cause a minute diminution of its speed, thereby causing pulley 13 to move toward stop 37, moving shaft 12 to the dot-and-dash position shown in Fig. 1. As is readily apparent, this increases slightly the effective radius of disc 9 and restores the desired speed.

It will be clear from the above that the invention provides a self-compensating drive, ensuring a substantially uniform turntable speed, and that the device is of such a construction that it is responsive to extremely small speed variations, thereby ensuring a constant speed within unusually close limits.

25 In addition, the mechanism has the advantages of simplicity and low cost, and may be readily assembled or adjusted.

The device disclosed may be used on either manual or automatic phonographs, and in addition, although illustrated with a single speed drive, may be readily modified for application to phonographs capable of operating at two different speeds. It will be understood, therefore, that the invention is susceptible of modification 30 within the scope of the appended claims.

I claim:

1. A drive mechanism for operating a turntable at a desired speed, comprising a driving element frictionally engaging the turntable; means 40 mounting said element for translational movement in response to variations in speed of the turntable, and variable speed drive means for said turntable responsive to the translational movement of said element for restoring the desired speed of the turntable.

2. A drive mechanism for operating a turntable at a desired speed comprising a driving element frictionally engaging the turntable and arranged for translational movement in response 50 to variations in speed of the turntable, a variable speed driving means for the turntable, and means responsive to the translational movement of said element for adjusting said driving means so as to restore the desired speed of the turntable.

3. A drive mechanism for operating a turntable at a desired speed comprising a rotary driving element operatively associated with the turntable to drive the same and arranged for translational movement generally parallel to the rotational plane of the turntable in response to variations in speed of the turntable, a variable speed driving means for the turntable, and means responsive to the translational movement of said element for adjusting said driving means so as to restore the desired speed of the turntable.

4. In a transmission having a turntable and a substantially constant speed motor, a self-regulating drive mechanism providing speed control for said turntable, said mechanism comprising a rotatable element driven by said motor and having driving zones of differing surface speeds; a second rotatable element in driven engagement with the driving surface of said first element, and means operatively associated with said second element and in driving contact with said turntable.

table, said last means being constructed and arranged to move the rotational axis of said second element in response to load variations on the turntable, thereby varying the point of contact between said first and second elements to compensate for variations in drag and resultant speed changes of said turntable.

5. In a transmission having a turntable and substantially constant speed motor, a self-regulating drive mechanism providing speed control for said turntable, said mechanism comprising a rotatable element driven by said motor and having driving zones of differing surface speeds, a second rotatable element in driven engagement with the driving surface of said first element, a shaft fixed to said second element and in driving contact with said turntable, and means mounting said shaft for rotational movement about two different axes, said last means being adapted to automatically effect limited rotation of said shaft about one of said axes in response to load variations on the turntable, thereby varying the point of contact between said first and second elements to compensate for variations in drag and resultant speed changes of said turntable.

6. In a transmission having a circumferentially flanged turntable and a substantially constant speed motor, a self-regulating drive mechanism providing speed control for said turntable, said mechanism comprising a rotatable element driven by said motor and having driving zones of differing surface speeds, a second rotatable element in driven engagement with the driving surface of said first element, a rotatable shaft fixed to said second element and carrying a driving member contacting a face of the turntable flange, and means mounting said shaft for pivotal movement about an axis intersecting its normal rotational axis, said last means being adapted automatically to effect such pivotal movement in response to variations in the load on the turntable, thereby varying the driving ratio between said first and second elements to compensate for variations in drag and resultant speed changes of said turntable.

7. In a transmission having a circumferentially flanged turntable and a motor, a self-regulating drive mechanism providing speed control for said turntable, said mechanism comprising a rotatable element driven by said motor and having driving zones of differing surface speeds, a second rotatable element in driven engagement with the driving surface of said first element, a rotatable shaft adapted to be driven by said second element and carrying a driving member, means urging said driving member into contact with the inside face of the turntable flange, and means mounting said shaft for pivotal movement about an axis intersecting its normal rotational axis, said last means being adapted to automatically effect such pivotal movement in response to variations in the load on the turntable and thereby vary the driving

ratio between said first and second elements, to compensate for variations in drag and resultant speed changes of said turntable.

8. In a transmission having a circumferentially flanged turntable and a motor, a self-regulating drive mechanism providing speed control for said turntable, said mechanism comprising a rotatable element driven by said motor and having driving zones of differing surface speeds, a second rotatable element in driven engagement with the driving surface of said first element, a rotatable shaft adapted to be driven by said second element and in driving engagement with a face of the turntable flange, means mounting said shaft for pivotal movement about an axis intersecting its normal rotational axis to vary the zone of contact between said first and second rotatable elements, and means for maintaining the driving engagement of said shaft with said flange during movement of said shaft about said intersecting axis.

9. In a phonograph having a turntable and a motor, a self-regulating drive mechanism providing speed control for said turntable, said mechanism comprising a disc driven by said motor, a rotatable element in driven engagement with the surface of said disc, drive means fixed to said rotatable element and extending between said element and said turntable, said drive means having a longitudinal axis normally disposed in predetermined relation to the plane of rotation of said disc, and mounting means for said drive means arranged to effect rotation of the longitudinal axis of said drive means to vary the driving radius of said disc, in response to variations in the speed of rotation of said turntable.

10. A construction in accordance with claim 9, wherein said mounting means comprises a pair of spaced apart bearings, one of which serves as a pivot for the rotational movement of the longitudinal axis of said drive means, and the other of which is carried by a pivoted arm which serves to limit and control the movement about said pivot.

11. In phonograph turntable driving means, a main baseplate, a member having one end thereof pivotally secured to said baseplate, a driving element mounted for rotation in the free end of said pivoted member, a pair of driving wheels fixedly secured to said driving element in spaced relation, one of said wheels being adapted to drive the turntable through a flange thereon, and the other of said wheels being adapted to be motor driven, a pair of stops limiting the angular movement of said member about its pivot, means urging said member toward one of said stops, means urging the turntable driving wheel into contact with the flange of said turntable, and pivot means mounting said shaft for limited rotational movement about an axis intersecting its normal rotational axis.

COLIN B. DALE.
